UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

SEPARABLE ATTACHMENT-PLUG.

1,103,251.

Specification of Letters Patent. Patented July 14, 1914.

Application filed December 4, 1909. Serial No. 531,432.

To all whom it may concern:

Be it known that I, REUBEN B. BENJAMIN, a citizen of the United States, residing at Chicago, in the county of Cook and State of Illinois, have invented new and useful Improvements in Separable Attachment-Plugs, of which the following is a full, clear, concise, and exact description, reference being had to the accompanying 10 drawing, forming a part of this specification.

This invention relates to improvements in attachment plugs of that class in which the part which makes connection directly 15 with a stationary socket may be separated, when desired, from the part which carries the binding terminals to which are secured the leading-out conductors.

The principal object of the invention is 20 to provide an attachment plug of the above class which is so constructed that when it is desired to manually separate the two parts thereof this may be done without jarring the fixture which carries the socket 25 with which connection is made. To this end the device is so constructed that by giving a slight rotation to the part which is grasped by the hand, this being the part which carries the binding screws and wires, 30 the parts will readily separate.

Heretofore, as separable attachment plugs have usually been constructed, the separation of the parts could only be effected by withdrawing one of the parts from the other 35 with a straight pull. This has proved to be objectionable in many instances, as where the socket with which connection is made forms part of a chandelier carrying a number of lamps and shades therefor. When 40 a direct pull is exerted to separate the parts the separation is resisted for a time until the force exerted becomes great enough to overcome the resistance of the clips or other parts which tend to hold the members of 45 the plug together, whereupon these members separate with a sudden jerk which is liable to cause damage to the chandelier, shades and the like. By the use of my invention this difficulty is overcome, it being 50 possible to separate one part of the plug from the other without any undue force being employed or vibration caused. Sockets as heretofore constructed have also been defective in that, to connect the parts together, it has usually been necessary to force 55

a head or other enlarged portion, with a snapping action, between a pair of springs or the like. The jarring effect resulting from this was objectionable for reasons stated above.

It is therefore a further object of this invention to provide a plug of the class described in which the two parts may be connected together without any jarring effect.

In the accomplishment of the above objects I provide a cap member which is arranged to be screwed into the stationary socket, which cap member carries a side contact and an end contact arranged for engagement with the corresponding contacts 70 of the socket.

I then provide a plug member from which extend the leading-out wires, said plug member being arranged to be inserted into the cap member and, when so inserted, to make electrical connection between certain contacts carried thereby and the contacts of said cap member, the contacts of the plug being electrically connected with the binding terminals to which the wires 80 are secured. Electrical connection is thus made between the wires and the contacts of the stationary socket.

I also provide means whereby an abnormal strain exerted in a direction which 85 would tend to cause the plug member to pull out of the cap member will not be resisted to such an extent as to prevent such separation, although any such strain as would ordinarily be placed upon the device 90 will be insufficient to cause the parts to separate.

I also provide means for preventing any jarring effect when the plug member and cap member are connected. The interlocking parts upon the two separable members are arranged to make connection when one of said members is thrust directly into the other. After the parts have thus become locked together sufficient resistance to the 100 separation of said parts is offered to prevent the same from separating under ordinary conditions, as above stated, but if a slight rotation is given to the plug member relatively to the cap member, said parts automatically unlock, the plug member being forced out of the cap member to some extent, thus insuring the parts remaining detached from each other.

In the accompanying drawings, Figure 1 110

is a side elevational view of the device with the two separable members put together; Fig. 2 is a bottom plan view of the upper or cap member, or that member which is arranged to be inserted into a socket; Fig. 3 is a top plan view of the lower or plug member; Fig. 4 is a bottom plan view of the plug member, the insulating cap which encloses the lower part of the same being removed; Fig. 5 is a longitudinal sectional view of the device with the separable members connected with each other; Fig. 6 shows the device with the members separated, the cap member being shown in section on the line 6—6 of Fig. 2, while the plug member is shown in elevation; Figs. 7 and 8 are sectional views of the upper portion of the plug member, the sections being taken on the lines 7—7 and 8—8 respectively of Figs. 3 and 4; Fig. 9 is a sectional detail view of the contact head of the plug, the section being taken on the line 9—9 of Fig. 6, looking in the direction of the arrows; Fig. 10 is a view showing fragments of the cap member and plug member of a modified form of my device; Fig. 11 is a fragmentary view showing the cap member and plug member of this modified form in plan; and Fig. 12 is a detail section taken on the line 12—12 of Fig. 10 looking in the direction of the arrows.

Referring now to the drawings, the cap member comprises an insulating base 10 which occupies the upper portion and extends beyond the upper end of a threaded metallic ring 11, which forms the outer side contact of the cap. Below the threaded portion of the ring 11 the latter is slightly contracted at 12, whereby a shoulder is formed upon which the base 10 rests, the base 10 being further secured in place by means of indented bosses 12^a formed upon the ring near the shoulder created by the contracted portion 12. In order that the base may be retained against outward movement in the ring, it is formed with a pair of oppositely disposed cavities 13, the material of the ring at its upper edge being bent over into these recesses at 14. Surrounding the lower portion of the ring is an insulating sleeve 15, the latter being prevented from slipping off the lower end of the threaded ring by forming the latter with a bead 16 at its lower edge and forming the insulating sleeve with a corresponding bead 17 which is occupied by the bead 16 of the ring.

The lower portion of the insulating base is chambered out at 18. From this chamber a passage extends upward through the base and opens at the outer end of the latter. A contact member comprising a strip 19, which extends across the upper end of the chamber 18 and is formed with a downwardly extending leg 20 at each of its ends, is secured in position in the chamber by

means of a hollow rivet 21 which extends through the aperture of the base and is headed over at its upper end to form a center outer contact for the cap member. When the cap member is screwed into a socket, 70 electrical connection is made by the threaded ring 11 with the threaded contact of the socket and by the contact member 21 with the center contact of the socket. The lower ends of the legs 20 are bent inwardly and then outwardly to form angular shoulders 22 for engaging and retaining a contact head with which the plug member is provided. The legs 20 are bent outwardly at 22^a, somewhat above the shoulders 22, to form an enlarged space between the legs for a purpose which will be described below. 75

Slidably mounted in the hollow rivet 21 is a plunger 23 having at its lower end a head 24, of somewhat greater diameter than the contact head of the plug member, which is forced toward the projections 22 by a spring 25 inserted between it and the lower end of the rivet 21. When the plug member is separated from the cap member the head 24 will be pushed by the spring 25 against the shoulders 22 (Fig. 6) and will hold them separated ready for the reinsertion of the contact head, but when the plug member is inserted into the cap member the head 24 will be forced inward against the action of the spring 25 until it reaches the enlarged portion 22^a, when the shoulders 22 are permitted to spring toward one another and grasp the contact head. 90

The lower or plug member comprises an insulating base 26 made somewhat cone-shaped and having a metallic ring 27 extending above its lower and larger portion, this ring being turned over inward upon a shoulder 28 with which the base is formed. The lower end of the ring 27 is drawn in under the base 26 and then extends downward to form a neck 29 having inner and outer screw threads thereon. A cap 30 encloses the threaded neck 29 and is formed of insulating material and has a neck portion 31 which is threaded or screwed up within the neck 29. Between the upper edge of the cap 30 and the shoulder caused by the drawing in of the material of the ring 27 is arranged an insulating ring 32 which extends laterally beyond the edge of the cap so as to be capable of being readily grasped by the fingers of the person using the plug. Upon the lower end of the base there is formed a projecting hump 33 which extends downward for a short distance into the neck 31 of the insulating cap. When the leading-out conductors are in position and the cap 30 is screwed up in place, the leading-out conductors are gripped between the inner edge of the upper end of the neck 31 and this hump 33, whereby the conductors are securely held and the occurrence is avoided. 100 105 110 115 120 125 130

ed of undue strain upon them, which strain would otherwise tend to tear the conductors from the binding terminals.

When the base 26 and the ring 27 carried thereby, which form the insertible part of the plug member, are thrust into the lower end of the cap member, electrical connection is made between the interior of the portion 12 of the ring 11 and the exterior 10 of the ring 27. To insure good electrical contact being made, the portion 12 of the ring 11 is formed with a number of inwardly projecting humps 34 which make rubbing contact with the ring 27. A binding screw 35 is provided for making electrical connection between one of the leading-out conductors and the ring 27, this binding screw being carried by a tongue 36 formed by cutting the ring 27 vertically at each side of 15 the screw 35, the tongue being set back into a suitable recess formed in the base 26. The binding screw 35 is provided with a nut 37 located in the recess in the base, this nut being prevented from rotating by the shape 25 of the recess. A passage 38 extends from the under side of the base up to the tongue 37, this passage being provided for the accommodation of the leading-out wire which will extend therethrough and emerge at the 30 left hand edge of the tongue 36 in position for attachment to the binding screw 35.

A chamber 39 extends down into the base 26 from the upper end of the latter. From this chamber a passage 40 extends downward and opens at the bottom of the base. 35 The upper portion of the chamber 39 is enlarged in diameter to receive a contact piece 41, the lower portion of which is cup-shaped. The contact piece 41 is held in position by 40 a plate 42 which is provided with a pair of prongs 43, the latter being bent downward at a right angle with the body of the plate and extending through openings or passages, which lead down from the chamber 39. The 45 lower ends of the prongs 43 are turned outward and extend laterally into suitable channels formed in the under side of the base 26. A binding screw 44 screws into the plate 42 and has its head sunk in the contact 50 piece 41. An opening 45 is formed in the contact piece 41 for the passage of the second leading-out conductor to the binding screw 44 after this conductor has been brought up through the passage 40 and 55 chamber 39.

The contact piece 41 is so shaped above the end of the base 26 as to form an oval stem 46, the greatest diameter of which is somewhat greater than the normal distance 60 apart of the shoulders 22 of the spring legs 20 upon the cap member. Above the stem 46, the contact piece is formed with a circular beveled head 47, the diameter of the head being equal to the greatest diameter of the 65 stem 46. The result of this is that the ex-

terior of the stem and the edge of the head 47 coincide at two diametrically opposite points, while at two other diametrically opposed points the head projects laterally considerably beyond the stem 46, thereby forming a pair of shoulders 48 which are adapted to engage beneath the shoulders 22 of the spring legs 20 upon the cap member when the plug member and the cap member are connected.

When the plug member is to be connected to the cap member, it is merely necessary to push it forward into the cap member, when the head 47 will enter between the legs 20 which, it will be remembered, are held apart by the head 24 of the plunger (Fig. 6). As the head 47 enters between the legs 20 the plunger head 24 is pushed backward until it reaches the enlarged portion 22 between the legs. There is then nothing to prevent the legs from springing together and they do this, the shoulders 22 engaging under the shoulders 48 of the head 47 (Fig. 5). When it is desired to disconnect the parts of the device, the plug member is twisted through 85 about 90 degrees. The effect of this is that the legs 20 are forced apart by the cam action of the oval stem 46 upon the shoulders 22. There is then no hold for the shoulders 22 upon the head 47, consequently the 90 plug member is forced outward by the action of the spring 25 and head 24, the latter following the head 47 downward and again taking up the position shown in Fig. 6.

In the modified form of my invention shown in Figs. 10, 11 and 12, the legs 20 are formed at their lower ends with angular jaws 49. In this case the contact piece 41 is formed with a square stem 50 instead of with the oval stem described above, the stem 50 and the jaws 49 being of corresponding shape. The head 51 of the contact piece is of a diameter equal to the diagonal length of the stem 50 so that the corners of the stem will coincide with the edge of the head. This construction operates in precisely the same way as the form described above with the exception that the plug member need 105 be turned to a less extent to effect a separation of the members.

By the arrangement of a head upon the lower portion and resilient fingers upon the upper portion arranged to grip under this head, there is afforded a form of lock which 110 is impositive, and which thus permits the device to be separated when an undue pulling strain is exerted upon the parts, this lock being, however, sufficiently positive in its action to give all needed security against 115 separation under normal conditions. By the provision of the irregular shaped stem of the contact piece of the plug member, means are provided whereby a slight rotation (at most a movement equal to one-fourth of a 120

complete revolution) of one part within the other unlocks the device. Very little effort is required in revolving the plug member to separate the members, thus but little twisting effect is imparted to the upper portion of the device. When the parts are brought to the proper angular relation to each other the plug portion is automatically thrust out by the action of the head 24, thus not only is no direct pull upon the plug required when the device is to be manually separated, but it is rendered impossible to give such a pull to the device if the plug is turned to the unlocking position. It will thus be seen that in unlocking one part from the other the action is exceedingly smooth, there being complete freedom from the sudden breaking away of one part from the other, with the consequent tendency to a reaction, which is common to other separable attachment plugs, and which reaction results in damage to fixtures, shades and the like. The plug also has the advantage that the connecting together of the parts is effected without any snapping or jarring action.

While I have shown and described the separable members as consisting of a cap and a plug insertible into the cap it is to be understood that I do not intend to limit myself to this precise construction, or in any other way to limit the scope of my invention except as pointed out in the appended claims.

Having thus described my invention, what I claim as new and desire to secure by Letters Patent, is:

1. In a separable attachment plug, a pair of body members, one of which is adapted to be inserted into a socket, gripping means carried by one of said members, and a contact head carried by the other of said members and arranged to be grasped by said gripping means when said members are put together, said contact head being provided with a cam projection arranged to release said gripping means when said members are rotated relatively to each other.

2. In a separable attachment plug, a pair of body members, one of which is adapted to be inserted into a socket, spring contact fingers carried by one of said members, and a contact head carried by the other of said members and arranged to be inserted between said spring contact fingers and grasped thereby when said members are put together, said contact head being provided with a cam projection arranged to force said contact fingers apart when the members are rotated relatively to each other.

3. A separable attachment plug comprising two separable members, one of which is adapted for insertion into a wall socket and the other of which carries binding

terminals for receiving leading in wires, interlocking contacts carried by said members, said contacts being arranged to lock together when the members are connected, means for releasing said contacts, and means for forcing said members apart when said contacts have been released. 70

4. A separable attachment plug comprising two separable members, one of which is adapted for insertion into a wall socket and the other of which carries binding terminals for receiving leading in wires, interlocking contacts carried by said members, said contacts being arranged to lock together when the members are connected, 75 means whereby said contacts are released upon one of said members being rotated with respect to the other, and means for forcing said members apart when said contacts have been released. 80

5. In a separable attachment plug, a member adapted to be inserted into a socket, a second member adapted to be connected with said first member, gripping means on one of said members, contact head carried by the other member and arranged to be grasped by the gripping means when said members are connected with each other, said contact head being provided with a cam projection arranged to release said 95 gripping means when the members are rotated, and auxiliary means tending to force said members apart. 90

6. In a separable attachment plug, a pair of members, one of which is adapted to be 100 inserted into a socket, spring contact fingers carried by one of said members, a contact head carried by the other member and arranged to enter between said contact fingers when said members are connected to each other, and auxiliary means tending to force 105 said members apart.

7. In an attachment plug, an outer member provided with an outer contact adapted for engagement with the corresponding contact of a wall socket, an inner member insertible into said outer member and provided with means for receiving leading-in wires, means tending to separate said members, means normally locking said members 115 together, and means arranged to unlock said locking means upon one of said members being rotated with respect to the other. 110

8. In an attachment plug, an outer member provided with an outer contact adapted for engagement with the corresponding contact of a wall socket, an inner member insertible into said outer member and provided with means for receiving leading-in wires, spring-pressed means tending to separate said members, means for normally locking said members together, and means for unlocking said locking means upon one member being rotated with respect to the other. 120 125

9. A separable attachment plug comprising a member, a contact head carried thereby, a second member for connection with said first member, a spring contact device carried thereby and adapted to engage under said head when the members are connected together, and means for holding said contact device out of the path of said head during the first part of the connecting movement and allowing said contact device to move into engagement with said head after the connecting movement has been completed.

10. A separable attachment plug comprising a member, spring contact fingers carried thereby having retaining shoulders thereon, said contact fingers being formed to create an enlarged space between them above said shoulders, a plunger arranged to enter between said fingers and retain them in a separated position, a second member, and a head carried thereby arranged to enter between said contact fingers and force said plunger upward into said enlarged space whereby said 25 contact fingers are enabled to close upon said head and retain it in position.

11. In an attachment plug, a pair of separable members, means tending to separate said members, a locking device for normally holding said members together so as to be 30 capable of separation upon a pull being exercised upon one of them, and means for releasing said locking device upon one of said members being rotated with respect to the other member.

12. In an attachment plug, two separable members, one carrying contacts for engagement with the contacts of a wall socket and the other carrying binding terminals, means tending to separate said members, a locking 40 device for normally holding said members together so as to be capable of separation upon a pull being exercised upon one of them, and manually operable means for releasing said members.

In witness whereof, I have hereunto subscribed my name in the presence of two witnesses.

REUBEN B. BENJAMIN.
